ELLIPSOGRAPH

John H. Barker, Watertown, Conn.

Application January 19, 1950, Serial No. 139,470

9 Claims. (Cl. 33—30)

1

This invention relates to drafting mechanisms for use in producing such geometrical figures as ellipses, elliptical and other curves, circles, and other configurations. Because devices of this type are usually employed to produce configurations of an elliptical nature, they are generally known as ellipsographs, and the present invention is so termed in the following description. However, it will be understood that many different figures and curves in addition to mathematically correct ellipses can be produced by the present device. Likewise, the invention is not limited to use in operating a scrib-
10 ing or marking device, but is also adapted to guide the movement of such other implements as welding electrodes, or such cutting tools as oxyacetylene torches and the like.

An object of the invention is to provide an ellipsograph or similar device having an improved and simplified construction for controlling the movement of the tool or scribe operating bar.

A further object is to provide a drafting mechanism such as an ellipsograph constructed and arranged to permit its use with such drafting instruments as T-squares, triangles, and so forth, for the purpose of producing a predetermined figure and accurately locate it on a given drawing.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

A feature of the invention is the provision on a supporting base of a guide bar for a scribing tool, cutting torch or the like, which is slidably mounted in a pair of supporting blocks, guided for sliding movement on the base in a direction at right angles to each other. The base is preferably rectangular with the two guide blocks movable at right angles to each other in directions parallel to the side and top edges. Each side of the base forms in effect a straight edge. As a result, the invention provides a useful drafting tool which can be used with T-squares, triangles and the like, to accurately and correctly locate the figure being produced on a given drawing. The guide bar is formed with perpendicular arms, one of which slidably engages each block, and each of which is parallel to one edge of the base. As a result, substantially any compound movement can be imparted to the bar and such movement will be accurately defined.

2

The guide bar is formed with a pair of slots at right angles to each other, each slot being parallel to one edge of the base. As a result, one slot is parallel to one arm of the guide bar and the other slot is parallel to the other arm. A pair of adjustable throw cranks are geared together for simultaneous movement and are connected to the bar so that one crank moves the bar in one perpendicular direction and the other crank in the other perpendicular direction. By varying the crank throws any desired compound movement can be imparted to the guide bar and the supported tool. Means are provided for accurately setting the cranks to predetermined measurements so that the figures produced by moving the guide bar will be accurately dimensioned.

These and other objects and features are accomplished by the present invention. In the accompanying drawing,

Fig. 1 is a plan view of a drafting device constructed in accordance with one embodiment of this invention;

Fig. 2 is a side elevation of the device shown in Fig. 1;

Fig. 3 is a perspective view of a detail;

Fig. 4 is a section on an enlarged scale showing further details;

Figs. 5 and 6 are sections on the lines 5—5 and 6—6, respectively, of Fig. 1, and

Fig. 7 is a perspective view of the device shown in Fig. 1.

The illustrated embodiment of the invention is shown as an ellipsograph having a base 11 with the edges thereof accurately formed at right angles to each other. A guide bar 12 is supported on the base and has arms 13 and 14 perpendicular to each other and slidably mounted in supporting blocks 15 and 16 respectively. One block 15 is generally of inverted T-shape and is slidable in a slot 17 extending along and parallel to one edge of the base 11. The other block 16 is of L-shape and is slidable in a slot 18 extending along another edge of the base at right angles to the first slot 17. Hence, the guide bar is universally movable in its plane by a sliding movement laterally of either or both the supporting slide blocks 15 and 16. Each block has top flanges overlapping the top faces of the respective arms 13 and 14 to snugly retain the arms in place in the blocks. The blocks are retained in their associated slots 17 and 18 by retaining plates 21 and 22 which overlie the slots and engage retaining shoulders 23 on the associated blocks.

Movement is imparted to the guide bar by a

handle 20, and the direction of movement is controlled by a pair of variable throw crank pins 24 and 25 on crank discs or gears 26 and 27 respectively, which are geared together and rotatably supported on the base 11 on studs 28 and 29. One crank pin 24 extends through and is movable along a slot 32 formed in the guide bar parallel to one arm 13 thereof. As illustrated, the slot 32 is formed in an arm 33 on the bar which is parallel to the arm 13. The other crank 25 extends through and is movable along a slot 34 parallel to the other arm 14 of the guide bar. As illustrated, this slot is formed directly in the arm 14. Hence, each crank is employed to move the bar in a direction parallel to one edge of the base 11 and perpendicular to the direction of movement produced by the other crank.

Each crank pin is radially adjustable on its supporting disk or gear. As illustrated, each crank is adjustable along a radial slot 35 formed on the surface of the associated gear or disk by spaced angle strips 36 secured thereto. Each crank pin has a head 37 located in the slot 35, as best shown in Fig. 6. A clamping washer 38 loosely surrounds the crank pin above the slot-forming strips 36. A clamping nut 41 is threaded to each pin and bears on the end of a sleeve 42 loosely surrounding each pin and extending freely through the slot in the associated guide bar. The sleeve and washer may be either separate members or integral. The sleeve is sufficiently greater in length than the thickness of the guide bar to prevent the nut 41 from clamping the bar. When the nut 41 is tightened on the associated crank pin the angle strips 36 will be clamped between the washer 38 and the head 37 whereby the pin will be secured against movement along the radial slot 35 while being freely movable along the slot in the guide arm 12. In order to adjust the position of the crank pin on its gear it is only necessary to loosen the nut 41 and move the pin along the slot 35, after which it can be secured in adjusted position by tightening the nut. It will be understood that in forming an ellipse, for example, the different axes thereof will be fixed by the distances the two pins are adjusted from the centers of the respective supporting gears. These distances can be accurately fixed in the present invention as hereafter described.

The arm 13 of the guide bar is shown in Fig. 7 as arranged to hold a scribe 40, but as above pointed out it can be used equally well to hold a cutting torch, welding electrode or any other suitable device, the invention being independent of the particular tool employed.

Assuming, however, that the invention is to be used to draw an ellipse, the crank pin 24 is adjusted a distance from the center of the supporting disk or gear 26 equal to one-half the length of one axis of the ellipse. This distance can be accurately measured on the scale 43 provided for this purpose on the retaining plate 21. In making this adjustment, the radial slot 35 in which the pin 24 is movable is first positioned parallel to the slot 17 in which the bar-supporting block 15 is mounted and, hence, parallel to one perpendicular edge of the base 11. The scale is so formed that when the pin 24 is aligned with the center of the supporting disk or gear 26 the edge of the block 15 is located at the beginning of the scale. Adjustment of the pin to the left in Figs. 1 and 7 can then be accurately measured off on the scale 43. When properly adjusted, the associated nut is tightened to secure the pin 24 in place. Thereupon, the bar is swung by the

handle 20 so as to rotate the other crank disk or gear 27 clockwise and swing the other crank pin 25 in a clockwise direction until the associated radial slot 35 in which this pin is adjustable is parallel with the slot 18 in which the bar-supporting block 16 is slidable and, hence, parallel to another perpendicular edge of the base 11. This crank is then adjusted a distance from the center of the associated gear 27 equal to the length of the other axis of the ellipse, and the securing nut for this crank then tightened. This adjustment can be accurately read on the scale 44 on the retaining plate 22 as adjustment of the pin is obtained by shifting the bar in a direction parallel to the slot 18 and thereby moving the block 16 in the slot along the scale. When the pin 25 is over the center of the gear 27 the edge of the block 16 will be located at the beginning of the scale and will be moved along the scale as the pin is moved farther from the gear center.

When both adjustments are completed and the clamping nuts tightened, the desired ellipse can be produced by moving the scribe bar so as to rotate the gears 26, 27. The cranks will impart the required compound movement to the bar to obtain the desired movement of the drawing tool or other implement.

It will be apparent that whatever figure is produced by the compound movement, its position and direction can be accurately located on a given drawing by properly positioning the edges of the base 11 by means of a T-square, triangle, or other drafting guide. The dimensions of the figure can be accurately prefixed and readily changed as needed.

The specific embodiment of the invention herein described can be variously modified and adapted within the scope of the appended claims.

Having thus set forth the nature of my invention, I claim:

1. An ellipsograph comprising a base member, a guide bar supporting a marking tool or the like comprising arms at right angles to each other, means supporting said bar on said base member for movement in two directions at right angles to each other, including a bar-supporting block for each arm, said blocks being slidable on said base member in directions at right angles to each other, a pair of variable throw cranks, means connecting one of the cranks to said bar to control the movement of said bar in one direction and means connecting the other crank to the bar to control the movement of the bar in the other direction, and means for shifting said bar.

2. An ellipsograph comprising a guide bar, bar-supporting blocks movable in directions at right angles to each other for guiding the movements of said bar, said bar being slidable in each block in a direction at right angles to the direction of movement of the block, a pair of cranks, means connecting each of said cranks to said bar for limiting the movement thereof in one of each of said directions, means for adjusting the effective lengths of the cranks, and means connecting said cranks for simultaneous rotation to impart to said bar a compound movement determined by the relative adjustments of said cranks.

3. An ellipsograph comprising a supporting base, a pair of blocks movable at right angles to each other on the base, a guide bar slidably supported on said blocks, a variable throw crank engaging a slot in said bar extending parallel to the direction of movement of one block, a second variable throw crank engaging a second slot in

said bar extending parallel to the direction of movement of the other block, a scale associated with each block whereby to measure the throw of each of said cranks, and means connecting said cranks together for simultaneous rotation, whereby movement imparted to said bar is controlled and defined by the relative positions of said cranks.

4. A mechanism comprising a base member, a tool-supporting guide bar having arms perpendicular to each other, separate means slidably supporting each of said arms, separate independent guide means on the base for each arm supporting means, the supporting means for each arm being movable on said base in a direction parallel to the other arm, and means controlling the movement of the bar in each direction comprising a pair of meshing gears and means connecting each gear to one of the bars respectively, whereby movement imparted to said bar causes a tool supported thereon to describe a predetermined figure.

5. A mechanism comprising a base member having side edges perpendicular to each other, a tool-supporting guide bar having arms perpendicular to each other, each arm being parallel to one of said side edges, separate means slidably supporting each arm of said bar, separate independent guide means on the base for each arm supporting means, the support for one arm being movable on the base in a direction parallel to one of said edges, and the support for the other arm being movable in a direction parallel to said other edge, and means controlling the movement of the bar in each direction comprising a pair of meshing gears and means connecting each gear to one of the bars respectively, whereby movement imparted to said bar causes a tool supported thereon to describe a predetermined figure.

6. A mechanism comprising a base member having side edges perpendicular to each other, a tool supporting guide bar having a pair of arms each perpendicular to the other and parallel with one of said edges, a block slidably supporting one arm and movable on said base member parallel to one side edge, a second block slidably supporting the other arm and movable on said base member parallel to a side edge at right angles to said first edge, a variable throw crank engaging a slot in said bar parallel to one arm, a second variable throw crank engaging a second slot in said bar parallel to said other arm, whereby movement of the guide bar with the throw of said cranks causes said blocks to move on said base member, and means on said base member cooperating with said blocks for indicating the throw of each crank.

7. A drafting mechanism comprising a tool-supporting guide bar having two arms perpendicular to each other, a pair of bar-supporting blocks mounted for movement at right angles to each other, each arm slidably engaging one of

said blocks for relative movement in a direction perpendicular to the direction of movement of the block, a pair of meshing gears, adjustable means mounted on one of said gears to control the movement of said bar in one of said directions, and adjustable means mounted on the other gear to control movement of said bar in the other of said directions, whereby movement imparted to said bar by rotation of the gears causes a tool supported thereon to produce a figure of predetermined shape and size.

8. A drafting mechanism comprising a supporting base, a tool-supporting guide bar having two arms perpendicular to each other, a pair of bar-supporting blocks mounted on said base for movement at right angles to each other, each arm slidably engaging one of said blocks for relative movement in a direction perpendicular to the direction of movement of the block on said base, a pair of meshing gears mounted on the base, adjustable means mounted on one of said gears to control the movement of said bar in one of said directions, and adjustable means mounted on the other gear to control movement of said bar in the other of said directions whereby movement imparted to said bar by rotation of the gears causes a tool supported thereon to produce a figure of predetermined shape and size.

9. A drafting mechanism comprising a tool-supporting guide bar having two arms perpendicular to each other and a pair of slots one parallel to each arm, a base member, a pair of bar-supporting blocks mounted for movement at right angles to each other on said base member, each arm slidably engaging one of said blocks for relative movement in a direction perpendicular to the direction of movement of the block, and a separate adjustable throw crank engaging in each slot, and means connecting said cranks for simultaneous rotation, whereby movement imparted to said bar causes a tool supported thereon to produce a figure of predetermined shape and size.
